Primary Examiner — Brett Miller*Assistant Examiner* — Jessica M Gebhart(74) *Attorney, Agent, or Firm* — Millen, White, Zelano & Branigan P.C.; Wan-Ching Montfort(57) **CLAIM**

The ornamental design for a lid of storage box, as shown and described.

DESCRIPTION

FIG. 1 is a top front perspective view of a lid of storage box showing my new design;

FIG. 2 is a front view thereof;

FIG. 3 is a rear view thereof;

FIG. 4 is a right side view thereof and the left side view being a mirror image;

FIG. 5 is a top view thereof;

FIG. 6 is a bottom view thereof;

FIG. 7 is a top rear perspective view thereof; and,

FIG. 8 is a bottom rear perspective view thereof.

The dashed broken lines in the figures show portions of the lid of storage box that form no part of the claimed design.
